UNITED STATES PATENT OFFICE

2,472,932

HOUSE MOVING APPARATUS

Bruce Adkins, Pharr, Tex.

Application October 10, 1947, Serial No. 779,082

3 Claims. (Cl. 214—1)

1

This invention relates to apparatus for transporting house structures, and more particularly to house moving apparatus of the truck trailer type.

A main object of the invention is to provide a novel and improved apparatus for lifting and moving house structures and the like, said apparatus being very simple in construction, easy to operate, and dependable in performance.

A further object of the invention is to provide an improved house moving apparatus which is relatively inexpensive to fabricate, sturdy in construction, and which greatly speeds up house moving operations.

Further objects and advantages of the invention will become apparent from the following description and claims, and from the accompanying drawings, wherein:

Figure 1 is an elevational view showing a house in the process of being transported by an apparatus constructed in accordance with the present invention.

Figure 2 is an enlarged fragmentary plan view of the lifting portion of the house transporting apparatus of Figure 1.

Figure 3 is a vertical transverse cross-sectional view taken on line 3—3 of Figure 2.

Figure 4 is a side elevational view of the structure illustrated in Figure 2.

Referring to the drawings, 11, 11 designate a pair of heavy carrier beams which are placed in parallel relationship beneath the structure, such as the house 12, which is to be moved. Journalled on each end of the beams 11, 11 is a pulley 13, said pulleys being rotatable around the longitudinal axes of the respective beams.

Designated at 14 is the rear portion of a conventional truck frame. Mounted transversely on and secured to truck frame 14 is a heavy cross beam 15. Journalled on the ends of cross beam 15 are respective pulleys 16, 16 which are rotatable in the transverse vertical plane of cross beam 15. Secured to the truck frame 14 and extending longitudinally thereof is a superstructure comprising parallel tubular beams 17, 17 rigidly braced by longitudinally spaced cross members 18 connecting said beams 17, 17. Secured in one of said cross members 18 and the under-lying truck frame 14 at the cross beam 15 is a vertical shaft 19. Journalled on shaft 19 between the su-

2

perstructure and the cross beam 15 is a drum 20 formed with annular flanges 21, 22 and 23 defining upper and lower reel sections 24 and 25. The bottom of the drum 20 carries a ratchet flange 26 and engaging the toothed periphery of said ratchet flange 26 is a pawl member 27 pivotally connected to cross beam 15 and biased into engagement with the periphery of the ratchet flange 26 by a spring 28 connected between said pawl member and a projection 29 carried by the cross beam 15. Secured to the lower reel section 25 and wound thereon is a winch cable 30 which is secured to a conventional winch device 31 carried on truck frame 14. Secured to the upper reel section 24 and wound thereon are a pair of cables 32, 32 which pass over the respective end pulleys 16, 16 of cross beam 15 and are respectively secured to said cross beam at 33, 33. The cables 32, 32 are crossed and looped beneath the pulleys 16, 16, as shown at 34, 34 and are adapted to be engaged with the end pulleys 13 of the carrier beams 11, 11, as shown in Figure 3. When the winch device 31 is energized, the cables 32, 32 are wound up on reel section 24 and exert a lifting force on the ends of carrier beams 11, 11 at the pulleys 13, 13. The pawl member 27 cooperates with the ratchet flange 26 to automatically lock the drum 20 in clockwise rotated position, as viewed in Figure 2, until said pawl member is manually released.

In operation of the apparatus, the carrier beams 11, 11 are first positioned beneath the structure 12 to be moved, in parallel relation thereunder and spaced apart by a distance substantially equal to the distance between pulleys 16, 16 of cross beam 15. The looped cable portions 34, 34 are then engaged under the pulleys 13, 13 of the beams 11, 11 adjacent one end of the structure 12 and said beams 11, 11 are lifted at said one end by the operation of winch device 31 until a dolly, such as shown at 35 may be positioned under the beams 11, 11 at the lifted ends thereof. The beams are lowered onto dolly 35 by releasing pawl member 27 and allowing the cables 32, 32 to unwind.

The above described procedure is repeated at the other ends of the carrier beams 11, 11, whereby the beams and the structure 12 will be raised to the elevated positions thereof shown in Figure 50 1. The structure 12 may then be transported by

the truck directly to its new site and lowered onto a suitable supporting foundation by reversing the above described procedure.

While a specific embodiment of a house moving apparatus has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. In an apparatus for transporting building structures, a pair of elongated carrier beams adapted to be positioned under a structure to be moved, each beam having a pulley journalled at each end thereof, the pulleys being rotatable in planes transverse to the beams, a motor truck, winch means carried on the rear portion of said truck, a transverse beam carried on said truck rear portion, pulleys journalled on the ends of said transverse beam, and a pair of cables extending from said winch means, each cable being looped over a pulley on said transverse beam and engaging under an end pulley of a carrier beam adjacent one end of the structure to be moved, the cable ends being secured to the truck rear portion, whereby the carrier beam ends will be elevated when the cables are wound up on said winch means.

2. In an apparatus for transporting building structures, a pair of elongated carrier beams adapted to be positioned under a structure to be moved, each beam having a pulley journalled at each end thereof, the pulleys being rotatable in planes transverse to the beams, a motor truck, a transverse beam carried on the rear portion of said truck, pulleys journalled on the ends of said transverse beam and being rotatable in the vertical plane of said transverse beam, a vertical reel rotatably secured on said transverse beam,

a pair of cables secured to said reel, each cable being looped over a pulley on said transverse beam and engaging under an end pulley of a carrier beam adjacent one end of the structure to be moved, the cable ends being secured to said transverse beam, and means on said truck for rotating said reel whereby the carrier beam ends will be elevated.

3. In an apparatus for transporting building structures, a pair of elongated carrier beams adapted to be positioned under a structure to be moved, each beam having a pulley journalled at each end thereof, the pulleys being rotatable in planes transverse to the beams, a motor truck, 10 a transverse beam carried on the rear portion of said truck, pulleys journalled on the ends of said transverse beam and being rotatable in the vertical plane of said transverse beam, a vertical reel rotatably secured on said transverse beam, a pair 15 of cables secured to said reel each cable being looped over a pulley on said transverse beam and engaging under an end pulley of a carrier beam adjacent one end of the structure to be moved, the cable ends being secured to said transverse beam, 20 winch means on said truck for rotating said reel, a toothed ratchet flange carried by said reel, a pawl pivoted to said transverse beam and engageable with said ratchet flange, and spring 25 means biasing said pawl into interlocking engagement with said ratchet flange.

BRUCE ADKINS.
